UNITED STATES PATENT OFFICE.

ADOLPH Y. S. ALBUM, OF MAYWOOD, ILLINOIS.

BOTTLE STOPPER.

Application filed May 25, 1922. Serial No. 563,473.

To all whom it may concern:

Be it known that I, ADOLPH Y. S. ALBUM, a citizen of the United States, residing at Maywood, in the county of Cook and State of Illinois, have invented a new and useful Bottle Stopper, of which the following is a specification.

The invention resides in the above stated objects and features and in sundry other details 10 features of construction which will later appear in the detail description of the invention.

In this specification and the annexed drawings, the invention is disclosed in the 15 form in which it is considered to be the best, but the invention is not limited to such form because it is capable of being embodied in other forms; and it is to be understood that in and by the claims following the description herein it is intended 20 to cover the invention in whatever form it may embody within the scope thereof.

In the drawings which disclose the preferred embodiments of the invention as at 25 present devised:

Figure 1 is a plan view of the cap or stopper constructed in accordance with the invention.

Figure 2 is a bottom view of the cap. 30 Figure 3 is an edge view of the cap.

Figure 4 is a plan view of the cap with a portion broken away to illustrate the tab reinforcing member.

Figure 5 is a view similar to Figure 4 35 showing a modified form of reinforcement.

Figure 6 is a plan view of another modified form of the cap.

Figure 7 is a view showing a further 40 modification of a cap equipped with a tab reinforcing means.

Figure 8 is a cross sectional view of a cap, shown in Figure 1, in position in a bottle, the bottle also being shown in section, and

45 Figure 9 is a plan view of a further modified form of cap.

The present invention is an improvement in bottle stoppers and is particularly useful in connection with milk bottle caps of the disk type, but it is to be understood that the invention is not limited to milk bottle caps as it is capable of use in connection with other bottle stoppers of more or less general use.

55 Heretofore, so far as applicant is aware, bottle caps or stoppers, which have been

provided with integral peripheral pull-tabs, have these tabs folded or creased on a line forming a substantial continuation of the peripheral edge of the caps. As it is 60 impossible to bend or fold the tab on a curved line, the result is that the tabs folded at the periphery of the cap bend on a straight line producing a flat surface on the peripheral edge at this point, which does 65 not properly fit or fill the usual internal groove or rabbet at the mouth or discharge opening of the bottle. Thus, the contents of the bottle are not tightly sealed, but will leak out at this point, if the bottle is tilted 70 or up-set, and will permit the ingress of water, dust, insects or other foreign matter into the bottle which contaminates its contents.

The present invention aims to overcome 75 all of these drawbacks by notching, grooving, scoring or creasing the tab not at the peripheral edge of the cap, but transversely at a point between the peripheral edge and the outer end of the tab, thus providing an 80 unweakened outwardly extending portion contiguous to the peripheral edge of the cap, which will permit a tight joint to be obtained at this point with the bottle.

Another object of the invention is to provide a bottle stopper, preferably of the ordinary disk type, with an integral pull-tab extending outwardly from its peripheral edge and to reinforce the tab in such a manner that it will not break or tear off 90 from the body of the cap when pulling upon the tab to remove the stopper or cap from the bottle.

Referring more particularly to the drawings wherein like characters denote similar 95 and like parts throughout the several views, 1 denotes a circular disk, of usual pasteboard or other suitable material, of dimensions to tightly fit in the mouth of a bottle which is to be used. The disk is formed 100 with an integral tab extending outwardly from the peripheral edge of the cap, the tab being of any suitable shape or formation. The tab is scored, indented, notched, or depressed to form a definite groove or incision 3 extending transversely of the tab at a point spaced from a line *a*, forming a continuation of the peripheral edge of the cap, and between this edge and the outer end of the tab. The other face of the cap, as shown in 110 Figure 2, is formed to provide for a depression in its outer end portion which pro-

vides a thumb or finger grip insuring a better hold to the tab when removing the cap from a bottle. The major central area of the face of the cap shown in Figure 2 is also 5 depressed slightly to provide the annular marginal raised portion 5 extending around the peripheral edge of the cap.

The advantage of scoring, notching or grooving the cap, a distance from the peripheral edge α of the cap is to provide a portion α which will not bend or crease on a definite line coinciding with a peripheral edge of the cap, and which portion α will be of sufficient area to tightly fit against the 10 vertical wall v of the usual internal groove or rabbet 6 of a bottle 7. This function of the portion α of the tab is facilitated by the definite and pronounced groove 3 which permits the tab to bend in the peculiar manner shown in Figure 8 and the portion α to tightly fit and fill the rabbet 6. It will thus be observed that a water tight fit is made at this point by the construction above recited, thus, tightly sealing the bottle 7 at this 15 point to exclude air and foreign matter from the bottle when the cap is pressed downwardly into the bottle opening by the usual capping machine. This tight joint cannot be obtained by weakening the tab at a point coincident with the peripheral edge of the 20 cap.

The groove 3 may be on either the top or under face of the tab, but it is shown in the present instance, as on the top face, because 25 in this form the best results are obtained.

It will also be observed in Figure 8 that the raised marginal portion 5 will tightly and frictionally engage the vertical wall of the rabbet 6 of the bottle, the diameter of the 30 cap being slightly in excess to the diameter of the rabbet.

In order to reduce the liability of the tab breaking or tearing from the body of the cap, during the capping operation or while 35 the cap is being removed from the bottle, the tab may be reinforced or anchored to the body of the cap by means of a thin flexible wire, thread or cord, or strip or layer of relatively tough material such as paper, wood 40 shaving fabric, metal or the like. This wire, thread or strip of material is embedded between the plies of paper or material forming the structure of the cap and extends longitudinally of the tab as clearly shown in Figures 4, 5 and 7, respectively.

In Figure 4 the reinforcing member 8 therein shown may take the form of a fine thin wire or a cord or thread as may be preferred and advantageous in each particular 45 case. The reinforcing member 9 is shown as being a strip of material which may consist of a strip of relatively tough paper, fabric, metal or the like. The reinforcing members 8 and 9 may extend diametrically 50 across the entire area of the cap and tab, or

may be shortened to extend only for a distance into the cap as indicated by the dotted lines in Figure 9.

In Figure 7 the reinforcing member 10 consists of a relatively wide layer of material having a projection extending into the tab. It is to be understood that the reinforcing member number 10 may assume any form or shape which is desired and advantageous. 75

In Figure 6 a modified form of cap is shown wherein no integral pull-tab is provided but where the reinforcing member 11, similar to the reinforcing members 8, 9 or 9^a extends outwardly beyond the peripheral edge of the cap and forms a pull-tab. 80

In Figure 9 the tab 2^a shown is provided with a groove or incision 3^a made by notching or cutting out a portion of the stock at a point adjacent the peripheral edge of the 85 cap.

In this view of the drawing, the reinforcing member 9^a, which may be of any of the materials above mentioned, is applied to one face of the cap and the tab. As shown, it is 90 applied to the surface of the cap opposite the incision or indentation 3^a, as clearly shown in dotted lines. However, the reinforcing member 9^a may be applied to either face of the cap and suitably attached thereto by adhesive, staples, or any other desired fastening means. 95

From the foregoing, it will be observed that applicant has provided improvements in milk caps which, aside from reducing the 100 cost of the usual tab-cap now in use, permits caps having integral and outwardly extending pull-tabs to be used and which overcome all previous drawbacks and disadvantages of such caps that have rendered them impracticable in commercial use. 105

Having thus described the invention, what I claim is:

1. A bottle cap having a pull-tab extending from the periphery thereof, said tab being weakened transversely at a point between the peripheral edge of the cap and the outer end of the tab for the purposes set forth. 110

2. A bottle cap having an integral pull-tab extending from the periphery of the cap and scored transversely at a point between the peripheral edge of the cap and the outer end of the tab to provide an unweakened portion connected with the cap between the peripheral edge of the latter and said scoring, for the purposes set forth. 115

3. A bottle cap comprising a flat disk body having an integral pull-tab extending from its periphery in the same plane thereof and of substantially equal thickness thereto, said tab being scored transversely at a point remote from the peripheral edge of the cap whereby an unweakened area of tab is provided between said scoring and the periph- 120

eral edge of the cap for the purposes set forth.

4. A bottle cap comprising a disk like body having an outwardly extending pull-tab at its periphery, one surface of said pull-tab being depressed at a central portion thereof to provide a finger grip.

5. A bottle cap having a pull-tab extending from the periphery thereof, said tab being weakened by notching or indenting one surface of the tab transversely adjacent the peripheral edge of the cap.

6. A bottle cap comprising a disk-like body having an outwardly extending peripheral pull-tab, a reinforcing member secured on said body, said member projecting beyond the periphery of said body and secured to said tab.

7. A bottle cap comprising a disk-like body having an outwardly extending pe-

ripheral pull-tab, a reinforcing member embedded in said body and tab and connecting the same.

8. A bottle cap comprising a disk-like body having an outwardly extending integral tab on its peripheral edge, a reinforcing member extending diametrically of the body and embedded in the body and said pull-tab, for the purposes set forth.

9. A bottle cap comprising a disk-like body having an outwardly extending integral pull-tab on its peripheral edge a flexible reinforcing member consisting of a layer of relatively tougher material incorporated in the disk body and having a projection extending into said pull-tab for the purposes set forth.

In testimony whereof I have hereunto set my hand.

ADOLPH Y. S. ALBUM.
